UNITED STATES PATENT OFFICE.

ISAAC G. WATERMAN, OF SANTA BARBARA, CALIFORNIA.

ELECTRICAL MIXING-VALVE.

No. 802,957.

Specification of Letters Patent.

Patented Oct. 24, 1905.

Application filed January 12, 1904. Serial No. 188,788.

To all whom it may concern:

Be it known that I, ISAAC G. WATERMAN, a citizen of the United States, residing at Santa Barbara, in the county of Santa Barbara and 5 State of California, have invented new and useful Improvements in Electrical Mixing-Valves, of which the following is a specification.

This invention relates to electrical mixing-10 valves.

The object of the present invention is the provision of an improved electrical valve mechanism especially adapted for use in connection with shower-baths, but also adaptable 15 to other uses whereby hot and cold water can be made to flow independently or mixed to the desired extent to bring them to the proper temperature for bathing or other uses by pressing electric buttons placed conveniently 20 to the user.

In a more detailed aspect the invention contemplates the electrical turning on or off of a valve to control the flow of the hot and cold fluids by the use of one electrical push-button 25 and the electrical operation of another valve of novel construction by another electrical push-button, successive manipulations of which gradually open or gradually close the valve to thereby obtain a desired mixture 30 of the fluids or either of them separately.

The invention resides in the novel features and combinations of parts set forth in detail hereinafter and recited in the appended claims.

In the accompanying drawings, Figure 1 is 35 a section on line D D of Fig. 5; Fig. 2, a section on line B B of Fig. 1; Fig. 3, a section on line A A of Fig. 1; Fig. 4, a section on line E E of Fig. 5; Fig. 5, a section on line C C of Fig. 1, and Fig. 6 a diagram showing the 40 electrical connections and push-buttons.

The hot and cold water pipes 1 and 2 lead into the supply-valve casing 3 through ports 4 and 5. The mixing-valve casing 6 has entry-ports 7 and 8, connected with exit-ports 9 and 10 in the supply-valve casing 3 by pipes 45 11 and 12 and is provided with an exit-pipe 13, adapted for connection to the shower-bath or to lead to the point of ultimate delivery of the water.

50 In the supply-valve casing is a rotary tapered valve 14, held seated by a spring-pressed ball 15 in a socket in a removable screw-threaded closure 16 entered in the valve-casing. The supply-valve 14 has parallel twin 55 ports 17 and 18 extending therethrough, which are adapted to independently connect the

ports 4 and 5 to ports 9 and 10 (see Fig. 4) when the valve is open and to completely cut off the flow of both hot and cold water when the valve is closed.

In the mixing-valve casing 6 is a tapered rotary valve 19, held in its seat by a spring-pressed ball 20 in a socket in a removable screw-threaded closure 21, entered in the valve-casing. The mixing-valve has a lune-shaped 65 port or groove 22 in its side, which is of sufficient length to connect either port 7 or 8 more or less with exit-pipe 13 or connect both of said ports more or less with said exit-pipe or altogether close communication between either port and the exit-pipe to entirely 70 cut off the water. According to the amount of rotation of this valve and the position it occupies, either hot or cold water will pass to pipe 13 in desired volume, or any desired admixture of hot and cold water can be obtained 75 or the supply entirely cut off through the valve 14 be open.

The valve-casings 3 and 6 have formed therewith the curved arms 23 (see Fig. 3) and 80 24, Fig. 2, and the heads 25 and 26 of the shell 27 of the respective solenoids 28 and 29 are fastened to these curved arms 23 and 24 by screws 30. The solenoids are separately wound and separated by heads 31 and 32 and 85 intermediate insulation 33, while the respective terminals 34 of solenoid 28 and 35 of solenoid 29 are led out, as shown in Figs. 1, 2, and 3.

90 Removable caps 36 and 37 cover the operative mechanisms at the upper and lower ends of the device.

The heads 31 and 32 have sockets 38 and 39, into which fit the ends of guides 40 and 41, which abut the inner faces of caps 36 and 37. 95

The valves 14 and 19 have stems 42 and 43, which pass through packings 44 and 45 and glands 46 and 47, which hold the packings, and said stems are centered in the respective guides 40 and 41. The stem 42 has secured thereto a ratchet-wheel 48, whose teeth are arranged in four sets of three teeth each, and a square nut 49 is also secured on said stem. A spring-pressed dog 50 engages the ratchet-wheel and prevents backward turning of the 105 same and the valve 14.

Slidable on the guide 40 and within the solenoid 28 is a tubular armature 51, to which at 52 is pivoted a pawl 53 having three teeth 54 pressed into engagement with ratchet-wheel 48 by a spring 55 on the armature. A coil-spring 56, interposed between the inner

end of the armature and the head 31, normally projects the armature, as shown in Fig. 1.

When the solenoid 28 is energized, the armature is drawn thereinto, causing the pawl 53 to engage and turn the ratchet-wheel and valve 14 a quarter-revolution, which causes the ports 17 and 18 to connect the ports 4 and 5 with ports 9 and 10, as shown in Fig. 4, if the valve was previously closed or if the valve was previously open to turn said ports 17 and 18 to the "off" position. (Shown by dotted lines in Fig. 4.) When the current ceases, the solenoid is deenergized and the spring 56 throws the armature to the position shown in Fig. 1, the pawl 53 riding idly on the ratchet-wheel, which is prevented from turning backward by the dog 50. When the armature is drawn into the solenoid, the shoulder 57 on the armature engages the near side of the square nut 49, and if the valve has been turned too far or too little this engagement rectifies the position of the valve and insures the perfect positioning thereof.

The valve-stem 43 has secured thereon a many-toothed ratchet-wheel 58, backward rotation of which and of said valve is prevented by a spring-pressed dog 59, pivoted at 60 to the guide 41. Slidable within the solenoid 29 is a tubular armature 61, which encircles said guide. Pivoted to this armature at 62 is a pawl 63, having a tooth 64 engaged with the ratchet-wheel 58 by a spring 65 on the armature. The armature 61 is normally pressed to the position shown in Fig. 1 by a coil-spring 66, interposed between it and the head 32. When the solenoid 29 is energized, the armature 61 is drawn thereinto, and the pawl 63 turns the ratchet-wheel and valve a short distance. On deenergization of the solenoid the spring 66 presses the armature to the normal position, (shown in Fig. 1,) the pawl 63 meanwhile riding idly on the ratchet-wheel and the valve remaining where formerly positioned. By successively energizing the solenoid 29 the valve is turned farther and farther and the lune-shaped groove 22 brought to such position that either hot or cold water or an admixture of the two can be obtained in any desired quantity and at any desired temperature or the valve can be completely turned off.

In Fig. 6 there is illustrated the most suitable system for the operation of the respective valves that I know of at the present time.

One of the terminals of solenoid 28 and one of the terminals of solenoid 29 are connected to the circuit 70, in which an electrical generator 71 is included, said circuit leading to the contacts 72 and 73 of the push-button temporary contact-switches A and B, various forms of which are set forth and claimed in several of my previously-filed copending applications. The other terminal 34 of solenoid 28 and terminal 35 of solenoid 29 lead by circuit 74 and 75 to the other contacts 76 and 77

of the switches A and B. The switches have a rotary four-point metal member 78, to which is secured a four-toothed ratchet-wheel 79. Through a stationary guide or bearing 80 slides a push-button 81, having a pivoted pawl 82 adapted to engage a tooth of the ratchet-wheel 79. The button is normally pressed to the position shown by a coil-spring 83. When the button is pushed in by hand, the pawl engages a succeeding tooth of the ratchet-wheel, and on releasing the button the spring 83 snaps the contact 78 a quarter-revolution, causing two of the points thereon to momentarily engage and then pass off the stationary contacts, thus momentarily completing the circuit and energizing the solenoid. Alternate hand manipulations of the switch A alternately open and close valve 14. Succeeding hand manipulations of the switch B turn the valve 19 farther and farther. The user first operates the switch A to open valve 14 and then operates the switch B as many times as necessary to obtain the desired flow and temperature of the water. When the supply is no longer needed, a single operation of switch A turns off the water, thus obviating the necessity of successively operating the switch B until the valve 19 is closed.

Having thus described my invention, what I claim as new, and desire to secure by Letters Patent, is:

1. In a valve, the combination with a valve-easing having a pair of ports leading thereto and a pair of ports leading therefrom, of a rotary valve having a pair of ports adapted to simultaneously open or close communication between the respective pairs of ports aforesaid, a single solenoid, an armature slidable in said solenoid, a spring for projecting the armature from the solenoid, and means operated by the armature for turning the valve a quarter-revolution on each complete operation of the armature, whereby alternate energizations of the solenoid open and close the valve.

2. The combination with a valve-easing having ports, of a rotary valve in said easing having a port in its side adapted, on more or less turning of the valve, to communicate more or less with said ports, a single electromagnet, an armature controlled by said electromagnet, and means for operating the valve from the armature step by step on successive energizations of the electromagnet.

3. The combination with a valve-easing having ports, of a rotary valve in said easing having a port in its side adapted, on more or less turning of the valve, to communicate more or less with said ports, a toothed wheel co-operating with the valve and having numerous teeth, a spring-actuated armature having means engaging with the teeth on movement of the armature in one direction and disengageable therefrom on movement of the armature in another direction, and a single electro-

magnet controlling the armature, whereby successive energizations of the electromagnet successively operate the armature and turn the valve step by step.

5 4. The combination with a valve-casing having ports, of a rotary valve in said casing having a port in its side adapted, on more or less turning of the valve, to communicate more or less with said ports, an operating member, a 10 toothed wheel on the valve having numerous teeth, and a spring-actuated member carried with the actuating member and adapted to positively engage the toothed wheel on one movement of the actuating member and to 15 idly engage said toothed member on the other movement of the actuating member, whereby successive operations of the actuating member turn the valve step by step.

5. The combination with a valve-casing having 20 two inlet-ports and one delivery-port, of a rotary valve in said casing having a port in its side adapted, on more or less turning of the valve, to cause either or both of the inlet-ports to communicate with the outlet-port, or 25 to completely close any or all of said ports, a solenoid, an armature slidable therein in one direction, a spring for operating the armature in the other direction, a wheel having numerous teeth and secured to the valve, and a spring- 30 actuated member carried by the armature and adapted to positively engage the toothed wheel on one movement of the armature and to disengage from said toothed wheel on the other movement of the armature, whereby successive 35 operations of the armature turn the valve step by step.

6. In a valve, the combination with independent sources for the delivery of independent fluids, of a mixing-valve adapted to mix 40 the fluids, and a controller-valve for turning on and off the supply of fluids.

7. In a valve, the combination with independent sources for the delivery of independent fluids, of a controller-valve for turning on 45 and off the supply of fluids, an electromagnet and armature for operating said controller-valve, a mixing-valve adapted to mix the fluids, and an electromagnet and armature for operating the mixing-valve.

50 8. In a valve, the combination with independent sources for the delivery of independent fluids, of a controller-valve for turning on and off the supply of fluids, an electromagnet

and armature adapted on alternate energizations of the electromagnet to open or close the 55 controller-valve, a push-button switch for causing the energization of the electromagnet, a mixing-valve for mixing the fluids, an electromagnet and armature adapted on successive energizations of the electromagnet to operate the mixing-valve to obtain greater or lesser mixing of the fluids, and a push-button switch adapted on successive manipulations to 60 successively energize the last-named electromagnet. 65

9. In a valve, the combination with independent sources for the delivery of independent fluids, of a controller-valve for turning on and off the supply of fluids, an electromagnet and armature for controlling said controller-valve, a rotary mixing-valve having means for 70 more or less mixing of the fluids as the valve is turned more or less, an electromagnet, and an armature controlled by the electromagnet having means co-operating with the mixing-valve to turn said mixing-valve step by step on successive energizations of the electromagnet. 75

10. In a valve, the combination with independent sources for the delivery of independent fluids, of a controller-valve for turning on 80 and off the supply of fluids, an electromagnet and armature adapted on alternate energizations of the electromagnet to open or close the controller-valve, a temporary-contact push-button switch for causing temporary energizations of the electromagnet on operation of said switch, a mixing-valve for mixing the fluids more or less according to the position of said mixing-valve, an electromagnet, an armature controlled thereby adapted on successive 85 energizations of the electromagnet to operate the mixing-valve to obtain more or less mixing of the fluids, and a temporary-contact push-button switch adapted, when operated, to 90 temporarily energize the last-named electromagnet and on successive manipulations to 95 successively energize said electromagnet to thereby open or close the mixing-valve more or less.

In testimony whereof I have signed my name to this specification in the presence of two subscribing witnesses.

ISAAC G. WATERMAN.
